Primary Examiner — Cynthia Ramirez*Assistant Examiner* — Gino Colan(74) *Attorney, Agent, or Firm* — Middleton Reutlinger(57) **CLAIM**

The ornamental design for a roof fan shroud, as shown and described.

DESCRIPTION

Cross-reference is made to U.S. patent application Ser. No. 15/292,239 titled "Roof Fan Assembly," filed on Oct. 13, 2016, and is expressly incorporated herein by reference. FIG. 1 is a perspective view of a roof fan shroud showing my new design;

FIG. 2 is a top plan view of the design of FIG. 1;
FIG. 3 is a front elevation view of the design of FIG. 1;
FIG. 4 is a rear elevation view of the design of FIG. 1;
FIG. 5 is a right side elevation view of the design of FIG. 1;
and,

FIG. 6 is a left side elevation view of the design of FIG. 1. The broken lines are included for the purpose of illustrating portions of the roof fan shroud that form no part of the claimed design.

1 Claim, 6 Drawing Sheets(56)
